UNITED STATES PATENT OFFICE.

JOHN M. DAVIDSON, OF BRADFORD, PENNSYLVANIA.

SUCKER-ROD FOR DEEP WELLS.

SPECIFICATION forming part of Letters Patent No. 324,922, dated August 25, 1885.

Application filed December 4, 1884. (No model.)

To all whom it may concern:

Be it known that I, JOHN M. DAVIDSON, a citizen of the United States, residing at Bradford, in the county of McKean and State of Pennsylvania, have invented certain new and useful Improvements in Sucker-Rods for Deep Wells; and I do hereby declare the following to be a full, clear, and exact description of the invention, such as will enable others skilled in the art to which it appertains to make and use the same.

This invention relates to the construction of metal sucker-rods for deep wells; and, broadly stated, it consists, primarily, in a metal sucker-rod section having a spiral twist throughout its length, and provided at one end with a threaded pin and at the opposite with a threaded box integral therewith, whereby lightness, together with stiffness or rigidity, is obtained; and, secondarily, in a metallic sucker-rod wherein the spiral twist is left-handed, or in reverse direction to the coupling-thread of the rod joint, whereby all danger from separation of the sections of the rod is avoided.

In pumping deep wells—such as oil-wells—the sucker-rod extends within the tubing down to within a short distance of the standing valve. In wells of a few hundred feet depth, (which embraces many, if not all, of the early oil-wells,) wooden sucker-rods were employed, because the essentials of strength, lightness, and cheapness were best obtained by the use of such material; but when wells began to be bored to fifteen hundred, (1,500,) two thousand (2,000) feet, and deeper, something better and stronger than the wooden sucker-rod was needed, and there is, therefore, a demand for a metal rod.

In order to obtain a very stiff or rigid sucker-rod with the least possible weight of metal, I give the rod a spiral twist, and I further utilize the spiral twist in the rod as a means of preventing the disconnection of the sections, by giving the rods a spiral twist in reverse direction to the thread which couples the sections, so that any friction against the rod either of the well-tube or fluid therein will tend to screw up the joints of the rod. These im-

provements I have embodied in a sucker-rod, one form of which is shown in the accompanying drawings, wherein—

Figure 1 represents my improved metal rod in elevation, and Fig. 2 is a cross section of the body of the rod.

A is the solid enlargement formed on one end of the rod for the support of the threaded pin *a*. B is the box, which is interiorly screw-threaded to receive the pin of another rod. By means of these boxes and pins any number of these rods can be joined together, forming a string of any desired length. The rod may be made in any shape or form, and is then twisted so as to form a spiral. This adds great stiffness to the rod, so that it can be made of metal of much less weight than would be required if it were not in the form of a spiral.

As shown in the drawings, Fig. 1, the spiral is twisted to the left hand. This is essential if the threads on the pins and in the boxes are right-handed, as they always are. If the body of the rod were twisted spirally in the same direction as the thread of the pins, the friction of the rods against the sides of the tubing would have a tendency to unscrew the joints; but when the twist of the spiral is in the opposite direction to the threads of the pins the tendency is to tighten the joints. Of course, this would not affect the joints if there were no friction on the sides of the rods.

I am aware that in the construction of drills a spiral twist has been given not only to the bit, but also to the stock, in order to convert that portion of the bit and stock back of the cutting-edge into a conveyer to conduct away the débris; and I am also aware that twisted lightning-rods of light metal have been provided with screw-joints, in some instances cast or riveted to the rod, and in others the sections connected by a detachable coupling-nut, which construction lacks the strength, stability, and non-separable character necessary for use in a deep well. Therefore I do not herein claim such subject-matter.

What I claim as my invention, and desire to secure by Letters Patent, is—

1. A section or length for deep-well sucker-

rods, consisting of a spirally-twisted metal rod having at one end a threaded pin and at the opposite a threaded box, said pin and box integral with the rod, substantially as and for 5 the purposes specified.

2. A section or length for deep well sucker-rods, consisting of a spirally-twisted metal rod provided with threaded connections, the twist of the rod being in reverse direction from

the thread of its connections, substantially as to and for the purposes specified.

In testimony whereof I affix my signature in presence of two witnesses.

JOHN M. DAVIDSON.
